UNITED STATES PATENT OFFICE.

JAMES B. BAIRD, OF CANTON, OHIO.

COOLING-FLOOR TILE.

1,119,789.

Specification of Letters Patent.

Patented Dec. 8, 1914.

Application filed August 2, 1913. Serial No. 782,575.

To all whom it may concern:

Be it known that I, JAMES B. BAIRD, a citizen of the United States, residing at Canton, in the county of Stark and State of Ohio, have invented a new and useful Cooling-Floor Tile, of which the following is a specification.

The object of my invention is to produce a floor tiling of such construction that, when a plurality are associated together, a floor of desired dimensions may be produced, within which may be circulated a cooling fluid, such as cool water. The floor is of such character as to be useful in rolling mills, glass houses and other buildings where the operations are productive of excessive temperatures, the invention being useful in rolling mills where the hot iron is driven over the same floor upon which the operatives are required to pass.

The accompanying drawings illustrate my invention.

Figure 1 is an elevation of a rolling mill flanked by my improved floors. Fig. 2 is a plan in partial horizontal section; and Fig. 3 a section on line 3—3 of Fig. 2.

The fundamental element of my improved floor is a unit tile or block 10 comprising top and bottom plates and side walls which thus form a hollow block of suitable dimensions having the water circulation chamber 11. It is desirable that the units 10 be of considerable size yet the walls and top and bottom plates should not be too thick, and for that reason I arrange within the chamber 11 a series of vertical partitions 12 extending between the bottom and top plates and serving to thoroughly brace and support said plates. The partitions 12 are interrupted at suitable points 13 so as to deflect the water currents, and opposite end walls are provided with openings 14 which register with similar openings in adjacent blocks so that the blocks may be arranged in connected series by means of tapered bushings 15 fitting openings 14 preferably by pressed fit. The initial wall of the first block of each series is provided with a tapped opening 16 to receive a supply pipe 16 and this pipe is connected by a suitable union 17 with a main line 18. The final block 10 of each series in its farthest wall is provided with a tapped opening 19 for an egress pipe 20 which is considerably smaller than the supply pipe 16 so that the

circulation of water through the blocks will be under material pressure.

Any desired number of series of blocks may be arranged in parallel series and clamped together by bolts 21 lying between adjacent series, rectangular washers 22 being placed beneath each clamping nut 23 so as to cover the gap between adjacent blocks and also so as to distribute the clamping pressure. I find it desirable in the production of these blocks to undercut them at their lower longitudinal corners, as indicated at 24, so as to form a pocket for the rod 21, thus making it possible to bring the upper longitudinal corners together with a reasonable degree of nearness as indicated at 25.

In utilizing this floor-tile I find it desirable to provide a supporting floor 30, conveniently of concrete, and this floor is provided with drainage channels 31 to take care of any possible leakages from the cooling floor in case the cooling medium is leaking. It is also desirable that the supporting floor be flanked by the channels 32 and 33, the supply pipe 18 being arranged in channel 32 and the discharged fluid passing into the channel 33 from which it is conveniently drained. Where water is used as the cooling medium the discharged water may be carried to the various water boshes used in the rolling mills, or may be carried (a portion of or all of it) to the boilers.

For rolling mill practice, and other places where there is heavy traffic, I deem it advisable to make the blocks of cast iron of a considerable size and for that reason the bottom plate, in the block as originally produced, is perforated at 35 owing to the provision of core prints for the support of the chamber-forming cores and also for the ready removal of the cores and the proper clearing of the interior. These openings are plugged by plugs 36 which may conveniently be of the ordinary tapered screw-threaded type.

The provision of the small outlet pipes 20, and the consequent possibility of maintenance of the cooling fluid under pressure, enables me to insure the most efficient contact between the cooling fluid and the walls of the block, thereby obtaining the greatest heat absorbing effect.

By the use of these cooling floors it is not only possible to protect the feet of the per-

son, but they also assist in the cooling of the entire atmosphere of the building in which they are placed.

The blocks may be produced from any suitable or desirable material, metal plate, terra cotta, cast iron, etc.

I claim as my invention:

1. A cooling floor comprising a plurality of hollow floor-blocks arranged in a series 10 having internal connections connecting adjacent blocks, a supply pipe and a discharge pipe, said discharge pipe giving an effective outlet smaller than the supply pipe.
2. A cooling floor comprising a plurality of hollow floor-blocks arranged in a series 15 having internal connections connecting adjacent blocks, a supply pipe, and a discharge pipe.
3. A cooling floor comprising a foundation 20 flanked by a channel, a supply pipe laid in said channel, a plurality of hollow floor-blocks laid end to end on the foundation and internally connected in series, connections between the interiors of one of said blocks 25 and the supply pipe, and a discharge pipe leading from the series, said discharge pipe giving an effective outlet smaller than the supply pipe.
4. A cooling floor comprising a foundation 30 flanked by a channel, a supply pipe laid in said channel, a plurality of hollow floor-blocks laid end to end on the foundation and internally connected in series, connections between the interiors of one of said blocks 35 and the supply pipe, and a discharge pipe leading from the series.
5. A cooling floor comprising a plurality of sets of hollow floor-blocks, the blocks of

each set connected in series by pressed fit nipples extending through adjacent walls, 40 a supply pipe connecting the interiors of the several sets in parallel and discharges for said sets the adjacent under corners of the blocks being undercut to form clamping-bar channels, and clamping bars extending 45 through said channels parallel with the nipple axes.

6. A cooling floor comprising a plurality of sets of hollow floor blocks, the blocks of each set connected in series, a supply pipe 50 connecting the interiors of the several sets in parallel and discharges for said sets the adjacent undercorners of the blocks being undercut to form clamping-bar channels, and clamping bars extending through said 55 channels.

7. A cooling floor comprising a plurality of sets of hollow floor-blocks, the blocks of each set connected in series by pressed-fit nipples 60 extending through adjacent walls, a supply pipe connecting the interiors of the several sets in parallel and discharges for said sets.

8. A cooling floor comprising a plurality of sets of hollow floor-blocks, the blocks of each set connected in series, and a supply 65 pipe connecting the interiors of the several sets in parallel and discharges for said sets.

In witness whereof, I have hereunto set my hand at Avonmore, Pennsylvania, this thirtieth day of July, A. D. one thousand 70 nine hundred and thirteen.

JAMES B. BAIRD.
